UNITED STATES PATENT OFFICE.

WALTER LOHREY, OF BLOOMFIELD, NEW JERSEY, ASSIGNEE TO MAGNA METAL CORPORATION, OF NEW YORK, N. Y., A CORPORATION OF NEW JERSEY

ELECTRIC FURNACE.

1,386,374.

Specification of Letters Patent.

Patented Nov. 8, 1921.

Application filed May 21, 1921. Serial No. 471,368.

To all whom it may concern:

Be it known that I, WALTER LOHREY, a subject of Germany, and a resident of Bloomfield, county of Essex, and State of New Jersey, have invented certain new and useful Improvements in Electric Furnaces, of which the following is a specification.

The present invention is a furnace designed primarily for the alloying of metals.

10 In alloying magnesium and certain other metals, special precautions must be taken to prevent oxidation and "burning" of the metal. It is to this feature my invention is particularly directed, one of the principal 15 objects of the invention being to protect the metal both in the melting and in the subsequent alloying stages from the destructive effects of oxidation.

Other objects are to effect a definite and 20 secure control of the several metals which are to be alloyed and to insure a thorough admixture and perfect distribution and amalgamation or true "alloying" of the metals.

25 These objects I have attained by means of a furnace of novel construction, one example of which is disclosed in the accompanying drawings. I wish it understood, however, that the furnace shown is primarily of an illustrative character and that, therefore, the structure may be modified in various respects without departure from the true spirit and scope of the invention as hereinafter defined and claimed.

30 Figure 1 in the drawings referred to is a vertical sectional view of the furnace, on substantially the plane of line 1—1 of Fig. 2.

Fig. 2 is a horizontal sectional view as taken on substantially the plane of line 2—2 40 of Fig. 1.

Fig. 3 is a front elevation, and

Fig. 4 is a top plan view of the furnace structure.

Fig. 5 is a vertical sectional view taken on 45 a transverse plane on substantially the line 5—5 of Fig. 1.

Fig. 6 is a broken rear view of the cover-lifting mechanism showing particularly the method of counter-balancing the same.

50 The particular furnace shown is designed for the alloying of two metals, such as zinc and aluminum with a third base metal such as magnesium.

Accordingly as shown in Fig. 1 there are 55 provided separate crucibles 10 and 11 for the

zinc and aluminum, arranged at opposite sides of the magnesium-melting and alloy-mixing crucible 12.

The main crucible is supported in a chamber 13 and is heated by electrical heating units 14 applied to or forming the walls of such chamber and similarly, the smaller crucibles 10 and 11 are mounted in chambers 15 and 16 containing electrical heating units 17.

60 The smaller crucibles 10 and 11 are supported at higher levels than the main crucible and are connected with the main crucible by suitable piping 18 controlled by valves 19. These valves have handles 20 65 provided at the tops of the crucibles so as to be within reach for easy operation when the cover of the furnace is removed.

70 The furnace cover is of special construction in that it may be lifted either bodily 75 to uncover the entire furnace top, or it may be operated in sections to uncover only the desired crucible chambers.

75 For lifting the cover as a unit, I have shown links 21 each connected with the body 80 of the cover at one end at 22 and centrally connected at 23 with the end of a forwardly arched slide 24 guided in brackets 25 on the back of the furnace structure and counterbalanced by a weight 26 having a chain 85 or cable connection 27 running over a sheave 28 and connected with the slide at 29. With this construction it is possible to effect the raising and lowering of the entire cover with comparative ease and when the cover is 90 raised, it will be apparent that full access is to be had to all three of the crucible chambers.

95 Access to the individual crucible chambers is had by way of openings provided in the cover over the respective chambers and normally closed by the removable cover sections 30, 31 and 32, these cover sections or slabs having suitable handles 33.

100 The spaces beneath the smaller crucible chambers 15 and 16 are utilized in the present disclosure to provide annealing or core-drying chambers 34.

105 The metals may be mixed in the main crucible mechanically, as by means of a propeller or other mixing device 35 carried by a shaft 36 having a bearing at 37 on the top of the crucible and provided at its upper end with a coupling element 38 detachably engaged by a corresponding coupling element 110

39 on the lower end of a shaft section 40 journaled in the cover. This upper shaft section is shown provided with a bevel gear 41 in mesh with a bevel pinion 42 on the 5 horizontal shaft 43, which is suitably journaled on the cover and provided with a hand wheel or other operating member 44.

After the admixture of metals is effected, the product is discharged from the main 10 crucible as by way of a discharge spout 45 extending from the bottom of this crucible and controlled by a valve indicated generally at 46 in Fig. 2.

To hold back the slag and impurities during the pouring operation, I have shown the 15 main crucible as having a partition wall 47 extending downward from the top thereof to near the bottom. The forward half of the crucible is shown closed over at the top 20 by a semi-circular cover 48 formed as a part of the crucible and the remaining half may be covered over by a removable cover.

In operation, the metals to be alloyed are placed in their respective crucibles and the 25 heat is controlled to bring the metals to a proper molten condition. In the case of alloying zinc and aluminum with magnesium, the heats in the several melting chambers will be approximately the same, but in 30 the case of alloying a metal of higher melting point, such as copper, higher temperatures and possibly longer melting periods would be necessary, but in each instance, the heat in the several chambers would preferably be governed to bring all the metals 35 to the proper alloying temperatures and conditions at approximately the same time. Thus in the example given, when the magnesium, aluminum and zinc are in proper 40 molten condition and at the right temperature for alloying, the valves 19 are manipulated to admit the subsidiary metals to the base metal and the stirrer may be operated to effect a complete combination of the 45 metals.

As the air is excluded during these operations, oxidation is reduced to a minimum, so that loss of metal by oxidation and the 50 formation of slag is therefore reduced to a minimum. Also, what slag is formed is "skimmed" or held back by the partition wall 47 in the main crucible. The several crucibles are readily charged through the charging openings provided in the cover 55 and if it becomes necessary to remove or repair the crucibles, this can be easily accomplished when the cover is lifted as at such times the chambers are wholly exposed and also, it will be noted, that in this cover- 60 lifting operation, the mixing shaft will be automatically uncoupled.

What I claim is:

1. A furnace of the character set forth having separate independently controlled 65 heating chambers, a mixing crucible and

alloy metal crucibles in said chambers and connections for enabling flow of metal from said alloy metal crucibles to the mixing crucible.

2. A furnace of the character set forth 70 having separate independently controlled heating chambers, a mixing crucible and alloy metal crucibles in said chambers and connections for enabling flow of metal from 75 said alloy metal crucibles to the mixing crucible, a substantially airtight removable cover over said chambers, said cover having charging openings therein over the respective crucibles and independently removable closures for said charging openings. 80

3. A furnace of the character set forth having separate independently controlled heating chambers, a mixing crucible and alloy metal crucibles in said chambers and connections for enabling flow of metal from 85 said alloy metal crucibles to the mixing crucible, a substantially airtight removable cover over said chambers, said cover having charging openings therein over the respective crucibles, independently removable closures for said charging openings, a stirrer in 90 the mixing crucible and driving means on the cover having a connection with the stirrer.

4. A furnace of the character set forth 95 having separate independently controlled heating chambers, a mixing crucible and alloy metal crucibles in said chambers and connections for enabling flow of metal from 100 said alloy metal crucibles to the mixing crucible, a substantially airtight removable cover over said chambers, said cover having charging openings therein over the respective crucibles, independently removable closures for said charging openings, 105 a stirrer in the mixing crucible and driving means on the cover having a connection with the stirrer, said mixing crucible having an outlet spout and provided with a partition wall extending down to near the bottom of 110 the crucible for holding back the slag.

5. A furnace of the character set forth having a main heating chamber and auxiliary heating chambers at different sides of the same, a mixing crucible in said main 115 chamber and alloy metal crucibles in the side chambers, flow connections from the last-mentioned crucibles to the mixing crucible, means for independently controlling flow from the melting crucibles to the mixing 120 crucible, means for effecting an alloying of the metals in the mixing crucible and means for discharging the alloyed metal from the mixing crucible.

6. A furnace of the character set forth 125 having a main heating chamber and auxiliary heating chambers at different sides of the same, a mixing crucible in said main chamber and alloy metal crucibles in the side chambers, flow connections from the 130

- last-mentioned crucibles to the mixing crucible, means for independently controlling flow from the melting crucibles to the mixing crucible, means for effecting an alloying 5 of the metals in the mixing crucible and means for discharging the alloyed metal from the mixing crucible, the melting crucibles standing at higher levels than the mixing crucible and the furnace structure 10 having annealing and core-drying chambers beneath said melting crucibles.
7. In a furnace of the character set forth, a furnace body having separate chambers and independently controlled heating means 15 therefore, connected crucibles in said chambers, a cover over the top of the furnace chambers having openings in line with the crucibles, independently movable closures for said openings, a slide at the back of the 20 furnace structure guided for vertical movement, connections from said slide to the furnace cover and means for counterbalancing said slide and the cover connected thereto.
8. A metal alloying furnace having an 25 alloying crucible and alloy metal crucibles connected with and positioned to drain their contents into said alloying crucible, means for controlling said connections, a controllable discharge for the alloying crucible and controllable heating means for the several 30 crucibles.
9. In a metal alloying furnace, alloy metal crucibles connected to independently discharge their contents into an alloying crucible, means for independently heating the 35 contents of the several crucibles to the required alloying temperatures and means for maintaining said crucibles and their connections in substantially air-excluding relation during alloying operations. 40
10. In a metal alloying furnace, a mixing crucible having a partition wall extending down toward the bottom of the crucible, said crucible having a discharge outlet at one side of said partition wall and alloy metal 45 crucibles connected to discharge into the mixing crucible at the opposite side of said partition wall.

In witness whereof, I have hereunto set my hand this 7th day of May, 1921.

WALTER LOHREY.
